UNITED STATES PATENT OFFICE.

RANSFORD E. VAN GIESON, OF BROOKLYN, NEW YORK.

AUTOMATIC CLASP AND LIFTER FOR PHOTOGRAPHIC PLATES.

SPECIFICATION forming part of Letters Patent No. 319,359, dated June 2, 1885.

Application filed January 29, 1885. (No model.)

To all whom it may concern:

Be it known that I, RANSFORD E. VAN GIESON, of Brooklyn, in the county of Kings and State of New York, have invented a new and 5 useful Improvement in Holders for Photographic Plates; and I do hereby declare that the following is a full and exact description thereof, reference being had to the accompanying drawings, and to the letters of reference 10 marked thereon, making a part of this specification.

My invention relates to devices for manipulating photographic plates. Its object is to facilitate handling the plate without staining the 15 hands in the developing process, and to provide means for the support of the plate both in the bath and in its after treatment without touching the sensitive film upon its surface.

It consists of a double clamp, as hereinafter described, whose arms are combined with a spring operating to draw them together so that they may embrace automatically between them the opposite edges of the plate, and so bent as to overlap slightly its under face without contact 25 whatever with the opposite sensitized surface, and which will afford a handle for lifting the plate from the bath, lugs to prevent a contact of the plate with the bottom of the developing-tray, and a support for the plate when 30 tilted up on edge for inspection or for touching up.

In the accompanying drawings, Figure 1 illustrates my improved manipulating device attached to a glass plate and serving as a support for the plate when set up on edge for inspection. Fig. 2 is an edge view of the device when attached to a plate dipped in a bath, the developing-tray being in section. Fig. 3 illustrates a spiral coil substituted for a rubber band as a clamping-spring for the device. Fig. 4 is a side elevation of the device made of wire, and Fig. 5 illustrates in perspective a modification in which the inner ends of the arms are hinged together.

In Figs. 1 and 2 of the drawings my manipulating device is illustrated as constructed of a single flat strip of metal, A, bent or doubled in the middle to form two arms, B B, of equal length. These arms are automatically drawn 45 together with more or less power by means of an elastic band, C, preferably of rubber, made to encircle the two arms near to their angle of

divergence. The outer end of each arm is bent inward sufficiently to form a slight lip, D, adapted to engage the under side of the edge 55 of the photo-plate G, interposed between the arms, as shown in Figs. 1 and 2 of the drawings.

In doubling the strip A an eye or loop, E, is formed at the bend to serve as a convenient handle for the device, and to prevent the elastic band C from slipping off. A coiled metallic spring, C', may be substituted for the rubber band C to encircle the arms, as shown in Fig. 3, or be inserted between them, as shown at C" in Fig. 5.

Various other ways of applying springs to the arms to draw them automatically together will suggest themselves to mechanics skilled in the art, and I contemplate the use of any of these well-known equivalents.

The arms B B may be made of any suitable material, and I contemplate constructing them separately and pivoting them together at one end by a hinge-joint, as illustrated at F in Fig. 5 of the drawings, their automatic tension upon 70 an interposed plate being obtained by means of a spring or springs, as above described. When constructed of a flat plate or strip, A, I prefer to perforate the same with one or more openings, H. (See Fig. 1.) The arms may 75 likewise be made of round or flat wire, woven in suitable shape (see Fig. 4) instead of being constructed of a simple flat plate or strip, as shown in Fig. 1.

In the use of the device the photographic 85 plate G to be manipulated is interposed between the arms B B, which are spread apart so that their ends may engage the opposite edges of the plate, with the lips D D slightly overlapping the under surface thereof to support 90 and confine the plate between the arms. The tension of the elastic band or spring C will operate to hold and secure the clasping-arms so firmly to the plate as that the latter may be lifted and carried thereby without danger of 95 its accidentally dropping or slipping therefrom, and the plate may be supported thereby on edge, as shown in Fig. 1, or supported in a developing-tray, T, as shown in Fig. 2, the lips D D, serving in the latter case to uphold 100 the face of the plate above the bottom of the tray permit a free circulation of the bath fluid over the same, and prevent its adhesion to the bottom or "suction."

The plate may be lifted from the bath by means of the arms, and examined, and, if need be, replaced without soiling or staining the fingers by their contact with the chemicals in the bath.

The arms B B may be made of metal, hard rubber, gutta-percha, or any suitable material adapted to the purpose.

I am aware that clamps and clasps have been patented for use as stocking-supporters and napkin-holders, which are constructed of two spring arms or jaws made to spring automatically apart, and to be closed by sliding ring or loop, or a lever adapted to force the jaws together. My device differs essentially therefrom in that the arms are combined with a spring operating automatically to close upon and hold an interposed plate.

I claim as my invention—

A photo-plate holder constructed of the two connected diverging arms B B, whose outer ends are provided with inwardly-projecting lips D D, in combination with the elastic band C, encircling said arms to draw them automatically together, substantially in the manner and for the purpose herein set forth.

In testimony whereof I have signed my name to this specification in the presence of two subscribing witnesses.

RANSFORD E. VAN GIESON.
